J. A. BAKER

TONGS SUPPORT

Filed May 3, 1923

Inventor
John A. Baker

by
John T. Baker
his Attorney.

UNITED STATES PATENT OFFICE.

JOHN A. BAKER, OF LOS ANGELES, CALIFORNIA.

TONGS SUPPORT.

Application filed May 3, 1923. Serial No. 636,428.

To all whom it may concern:

Be it known that I, JOHN A. BAKER, a citizen of the United States, residing in Los Angeles, in the county of Los Angeles, 5 State of California, have invented new and useful Improvements in Tongs Supports, of which the following is a specification.

This invention relates to devices utilized for suspending tools during their application to work and during their operation on the work.

The construction and advantageous features of my device may be best explained by describing an application thereof to a 15 typical tool. As well casing and rotary tool joint tongs are customarily suspended during application and operation, I will describe my device as applied to such tools. However, following specific references to 20 tongs as the suspended tool are not to be construed as limiting the application of my device thereto.

Casing tongs are of considerable bulk and weight and in order that they may be 25 manipulated with the requisite speed and ease, are ordinarily counter-balanced, the counter-balancing weight being connected by a chain or cable to a suspension device mounted on the tongs. The usual suspension 30 device is of the three point type, that is, it consists of three separate suspension members attached to the tong handle and joined to a single cable ring in a manner to balance the tongs in a substantially horizontal plane.

It is one of my objects to provide a 35 suspension device provided with swivel tool connections allowing movement of the tool about its longitudinal axis whereby it may 40 adjust itself to canted work without imposing a twisting and breaking strain on the tong jaws.

I have further provided a two-joint suspension device wherein the supporting 45 structure may be rigid, the suspension members being either rigidly connected or made up of a single member bent to form a yoke.

Further objects and novel features of 50 my invention will be more fully described in the following specification, reference being made therein to the accompanying drawings, in which—

Fig. 1 is a side elevation of pipe tongs equipped with my device, the swivel connections being shown in section; Fig. 2 55 is a vertical section on line 2—2 of Fig. 1;

and Fig. 3 is a vertical section on line 3—3 of Fig. 1.

In Fig. 1, I have illustrated pipe tongs 9, indicating the handle or lever thereof 60 at 10, the jaws at 11, and the usual eye at 12. The tongs 9 are shown applied to work in the form of a vertically extending pipe W.

The suspension members of my device 65 are indicated at 13 and 14 and comprise a single rod bent in the form of a yoke and looped at 15 to form an eye or ring for the convenient attachment of a supporting chain or cable 16. It will be noted 70 that member 13 extends approximately in vertical alignment with the supporting chain 16 and carries the major portion of the weight of tongs 9, while the offset supporting member 14 supports a lesser weight 75 13 and serves to longitudinally balance the tongs. Member 14 is bent to provide a stretch 17 extending in substantially parallel relation to member 13.

The bearing members or disks 18 and 19 80 of the swivel joints 20 and 21, respectively, are provided with polygonal apertures 22 and 23, respectively, whereby they may be non-rotatively supported on handle 10, and are preferably made up of separable halves 85 clamped together in gripping relation on the handle by means of bolts 24 which pass through opposed ears or lugs 25. Disks 18 and 19 are provided with peripheral grooves 26 and 27, respectively, adapted to receive 90 the internal annular flanges 28 and 29 provided on swivel straps or collars 30 and 31, respectively, which latter encircle the disks in a manner to render them capable of axial rotation. Collars 30 and 31 are provided 95 with internally threaded sockets 32 and 33, respectively, adapted to receive the threaded extremities of rods 13 and 14, respectively. Members 13 and 14 are relatively arranged and so proportioned in length as to carry 100 disks 18 and 19, and hence swivel joints 20 and 21, in axial alignment.

Collars 30 and 31 are preferably halved as indicated in Figs. 2 and 3 to allow them 105 to be removably mounted on their respective disks, bolts 35 passing through opposed ears 34 being adapted to join the halves. The co-action between grooves 26, 27 and flanges 28, 29, respectively, prevents lateral displacement of the collars 30, 31 from their respective disks. It will readily be seen that should the work W be canted in a

vertical plane perpendicular to the axis of the tongs 9, swivel joints 20 and 21 allow axial movement on the part of the tongs, hence maintaining the axis of the apertures 5 of jaws 11 coincident with the axis of work W, and thus eliminating all twisting strain on the tong jaws.

It is obvious that various structural changes may be made in the device as illustrated without departing from the spirit of 10 my invention. For instance, disks 18 and 19 may be formed integral with the tongs handle or be formed by turning down portions of the handle to provide a cylindrical bearing surface thereon. Again, disks 15 18 and 19 need not be halved but may each be formed of a single piece suitably apertured to be slipped into position on the handle from one end thereof. Various 20 means may also be utilized for preventing lateral displacement between the collars and disk elements of the swivel joint. Therefore I do not wish to be limited to the embodiment of my invention as disclosed in 25 the accompanying drawings except for such limitations as a fair interpretation of the appended claims may import.

Having described a preferred form of my invention, I claim:

30 1. A tool suspending device comprising a yoke, axially aligned swivel joints carried by the arms of the yoke and adapted to be connected to the tool in a manner to render the tool capable of axial rotation.

35 2. A tool suspending device comprising a suspension rod, a swivel joint on said rod adapted to be connected to the tool in a manner to render the tool capable of axial rotation, and a balancing member extending 40 from said rod and adapted to be swivelly connected to said tool at a point spaced apart from the first mentioned swivel joint connection.

45 3. A tool suspending device, comprising a suspension rod, a swivel joint on said rod adapted to be connected to the tool, a balancing member extending from said rod, and a swivel joint on said balancing member adapted to be connected to said tool at a point spaced apart from the first mentioned 50 swivel joint, said swivel joints being axially aligned whereby the tool is capable of axial rotation.

55 4. A tool suspending device comprising a suspension rod, a bearing member adapted to be connected in axial alignment with the tool, and a supporting strap carried by said rod and adapted to encircle said bearing member in a manner to render said bearing member capable of axial rotation.

60 5. A tool suspending device comprising a yoke, axially aligned swivel joints carried by the arms of the yoke, and tool connecting means provided on said joints.

6. A tool suspending device comprising a

rod bent to form a yoke, an eye formed in said rod for receiving a supporting cable, and axially aligned swivel joints carried by the extremities of the rod and adapted to be connected to the tool.

70 7. A two point suspension device for tools, embodying a member having swivel connection with the tool at two points therealong, said swivel connections being in axial alignment whereby the tool is capable of 75 axial rotation.

8. A tool suspending device comprising a rod, means for suspending the rod, a swivel joint on said rod adapted to be connected to the tool in a manner to render the tool capable of axial rotation, and a balancing member attached at one end to said suspension means and attached at its other end to the tool at a point spaced apart from said swivel joint connection.

85 9. A tool suspending device comprising a rod, means for suspending the rod, a swivel joint on said rod adapted to be connected to the tool in a manner to render the tool capable of axial rotation, a balancing member attached at one end to said suspension means, and a swivel joint connection between the other end of the balancing member and said tool.

90 10. A tool suspending device comprising a rod, means for suspending the rod, a swivel joint on said rod adapted to be connected to the tool in a manner to render the tool capable of axial rotation, a balancing member attached at one end of said suspension means, and a swivel joint connection between the other end of the balancing member and said tool, said swivel joints being in axial alignment.

105 11. A tool suspending device comprising a suspension rod, a bearing member adapted to be connected in axial alignment with the tool, a supporting strap carried by said rod and adapted to encircle said bearing member in a manner to render said bearing member capable of axial rotation, and coacting means on said bearing member and strap adapted to prevent their relative displacement.

110 12. A tool suspending device comprising a suspension rod, a bearing member adapted to be connected in axial alignment with the tool, a supporting strap carried by said rod and adapted to encircle said bearing member in a manner to render said bearing member capable of axial rotation, said strap including two members, one member being attached to the rod, and the other member being clamped to said one member.

120 13. In a tool suspending device that includes a suspension member and a supporting collar carried thereby, a multipart bearing member rotatably mounted in said supporting collar and adapted to be secured to the tool.

125 14. In a tool suspending device that in-

cludes a suspension member and a supporting collar carried thereby, a multipart bearing member rotatably mounted in said supporting collar, said bearing member comprising a disk made up of a plurality of segments which are complementarily apertured to take the handle, and means for clamping the segments together.

15. In a tool suspending device that includes a suspension member and a supporting collar carried thereby, a multipart bearing member rotatably mounted in said sup-

porting collar, said bearing member comprising a disk made up of a plurality of segments which are complementarily apertured 15 to take the handle, means for clamping the segments together, and coacting means on the segments and collar adapted to prevent their relative displacement.

In witness that I claim the foregoing I 20 have hereunto subscribed my name this 19th day of April 1923.

JOHN A. BAKER.
